UNITED STATES PATENT OFFICE.

FRANK G. FENCL, OF OAKLAND, CALIFORNIA.

MACHINE FOR KNOTTING SPRINGS.

Application filed July 5, 1927. Serial No. 203,422.

This invention relates to an intermittent gear drive, one use of which is in connection with a spring knotting machine. This particular object is to knot one end or both ends of a spiral bed or seat spring around the adjacent member of the spiral in order to provide a construction which will have each end of the bed or seat spring of a given diameter. The present invention relates to the intermittent drive for actuating the spring holder and the twisting device for twisting the ends of the wire around the next adjacent member of the spiral.

Another object of the invention is to provide a driving device which will start the apparatus into motion from a slidable key and fixed pin thereby permitting the gears for operating the twister gear to remain always in mesh, and in that way prevent the gear breakages which happen very frequently with the ordinary types of starting mechanisms of this character.

Another object of the invention is to provide means for stopping the individually and separately moving parts of the apparatus in a given position with respect to each other at the end of each movement.

Another object of the invention is to enable the apparatus to be rotated reversely by hand whenever it happens that a spring gets stuck in the twisting gear.

Another object of the invention is to provide a driving mechanism for a gear movement which is applicable to any apparatus where one or more gears are to be intermittently operated as in a punch press, a shear, or any other mechanism of that character.

Other objects of the invention will be apparent as the description proceeds.

An embodiment of the invention is shown in the accompanying drawings in which the same reference numeral is applied to the same portion throughout the several figures of the drawings and of which there may be modification.

Figure 1 is a plan view of a portion of the driving assembly with parts cut away for purposes of illustration.

Figure 2 is a plan view of the bottom

spiral of a bed or seat spring illustrating the product produced by this apparatus.

Figure 3 is an end view of the driving mechanism shown in Figure 1.

Figure 4 is a vertical sectional view of the driving apparatus shown in Figure 1.

Figure 5 is an end view of the driving collar.

Figures 6, 7, and 8, respectively, are a side elevation, plan and end view of one of the slidable keys used in the driving apparatus.

Figures 9 and 10 are respectively side elevations and end view of the centering stop for the gear.

Figures 11 and 12 are respectively a plan view and side elevation of the cam for moving the slidable keys.

Figure 13 is a view in end elevation of the driving gear, the driving cam and the twister gear, showing the spring holding table in position ready to hold a spring.

This apparatus is intended for the purpose of intermittently driving a wire coiling gear, the object of which is to produce the twist A at one end of a spiral bed or set spring B (see Fig. 2) and the principal object of the invention is to produce a device in which the gears always remain in mesh so as to prevent the breakage of individual teeth and to produce a stronger apparatus capable of starting with less shock to the starting apparatus, and the invention in this case lies in the starting apparatus and not particularly in the coiling apparatus, which coiling apparatus is in use in a number of different wire coiling machines of this kind.

The numeral 1 is a fixed bearing shown in plan elevation in Figure 1 which has a revolute shaft 2. This shaft is provided with any suitable mechanism not forming a part of this invention, which starts it and turns it once and then releases it, all of the other steps of the present invention being accomplished by the automatic clutch mechanism shown within the fixed bearing 3.

The shaft 2 has a cam 4 secured thereto, which cam has a track to receive a roller 5, said roller being secured to an arm 6 by means of the threaded bolt 7 and nut 8. The

arm 6 is really a bell crank, and has the depending arm 9 pivotally mounted to a fixed frame at 10. This arm is provided with a table 11 and with a grooved holder 12 to receive the wire coil, said holder 12 having a pivotally mounted body 13 carried by the pin 14, which body is pulled down against the holder 12 by means of a fixed roller 15, said roller being shown in dotted lines merely for purposes of illustration, and to bring the body 13 down against the coil wire to hold it in a fixed position in the slotted twister gear 16, while the twist A is being made, said twist usually consisting of one or two turns at the end of the coil.

The slotted twister 16 is driven by the auxiliary gear 16', which is in mesh with said twister and with the main drive gear 17. The relation of the driving gear 17 to the twister gear 16 is such that the precise movement of the twister gear will be attained on each driving operation.

The driving gear 17 has a hub 18 connected thereto, which hub is journaled in the bearings. The ring 19 holds the two keys 20 and 21 in the position shown in Figure 4, while spiral springs 23 and 24 hold said keys resiliently to the right Figure 4, except when compressed by the movement of the curved cam 25, which cam is secured to the inside of the bearing 3 by means of two bolts 27 and 28. The ring 19 is held in place by two set screws 19'.

Secured in a drill hole in the bearing 3 is a latch 30, said latch being normally held in the position shown in Figure 4 by means of the spiral spring 31, the latter being held in place by means of the threaded plug 32.

40 Keyed to the shaft 2 is the collar 33, said collar having two driving pins 34 and 35 projecting therefrom and against which the ends of the keys 20 and 21 bear during the course of movement of the apparatus.

45 The operation of the apparatus is as follows: Assuming the shaft 2 to be started for a single revolution by any suitable mechanism, the first thing that will occur will be for the cam 4 to draw the table 11 toward the twister gear 16, this will bring the coil into the twister gear where it will remain during the remainder of the movement of the apparatus while producing the knot A. When brought up to the center of the twister gear the next movement will be for one of the sliding keys, 34 or 35 to engage one of the pins 20 or 21 with the result that the gear 17 will be started into motion and continued in motion for one-half of a turn whereupon the cam 25 will disengage whichever key 20 or 21 is engaged with one of the pins of the collar 33 and permit the gear 17 to stop, the latch 31 holding it in a given stopped position. At the time the gear 17 stops the slotted gear 16' will be restored to the

position shown in Figure 13, and the cam 4 will then have pushed the table 11 back to the position shown in Figure 13 so that the knotted wire and coil can be removed from the machine and the machine is then ready 70 for another operation.

If a spring happens to get stuck in the twister gear from any cause, the pin 35 enables either of the keys 20 or 21 to reversely drive the twister gear enough to disengage 75 the twisted wire ends.

It will be understood that the number of turns of the twister made during any revolution of the gear 17 may be varied by changing the number of teeth on the gear, by changing the length of the cam 25, by using more keys 20, or by using more stops 34 and 35. In any of these events the depressions in the driving gear in which the pin 31 acts must be changed accordingly so that the driving gear will be stopped in whatever location may be desired. While this mechanical movement has been described in connection with a knotting device for springs it is to be especially noted that there are many uses for it and that the intermittent operation of the gear 16 is only one of many uses to which it may be put.

Having thus described my invention, what I desire to secure by Letters Patent of the United States is as follows, but modifications may be made in carrying out the invention as shown in the drawings and in the above particularly described form thereof, within the purview of the annexed claims.

1. An intermittent driving mechanism for spring knotting machines comprising a sleeve, a driving shaft therefor, a collar fixed on said shaft, and means carried by the collar to pick up the sleeve and turn it one-half a revolution each time the driving shaft is turned one revolution.

2. An intermittent driving mechanism for wire knotting machines comprising a driving shaft, a cam for bringing the wire in position, a slotted wire knotting gear, a sleeve carrying a continuous gear, means whereby said sleeve will be driven one-half a revolution, and means to automatically engage and disengage said sleeve and gear each time the driving shaft is turned one complete revolution.

3. A knotting mechanism for springs, a driving shaft, a spring holding device, a slotted gear, a cam for bringing the spring holding device into the slotted gear, loosely mounted gear on the driving shaft, a fixed collar carried by the driving shaft, and a pair of slideable keys in said hub for driving said gear from said collar one half a revolution each time the driving shaft is turned one complete revolution, and means to automatically release and stop said gear each one-half revolution.

4. An apparatus of the class described

comprising a driving shaft, a wire coil holder, a slotted twisting gear, means connected with the driving shaft to bring the wire into the twisting gear, a collar carrying a gear for driving the twisting gear, a fixed collar on the driving shaft, a pair of slideable keys for turning the main gear one-half a revolution, a fixed cam for disengaging said keys from the driving mechanism alternately, and means to stop the main gear in a fixed position each one-half revolution.

5. In a machine of the class described a drive shaft, a fixed bearing therefor, a collar on said shaft, two stops on the collar, a cam on the drive shaft, a work holder operated by the cam, a tool for operating on the work, a drive gear, and means to operate said tool as well as to stop the same after a given part revolution of said drive gear. 15

In testimony whereof I have hereunto set 20 my hand this 28th day of June, A. D. 1927.

FRANK G. FENCL.
